UNITED STATES PATENT OFFICE

BYERS W. KADEL, OF BALTIMORE, MARYLAND

HAND BRAKE FOR RAILWAY CARS

Application filed December 7, 1926. Serial No. 153,054.

This invention relates to hand brakes for railway cars or the like and has among its objects to provide an efficient brake of the geared type. A more specific object is to provide a geared hand brake which may be housed in or beneath the brake step, also a geared brake in which a portion of the brake step is utilized as a portion of the gear casing. Another object is to provide a metallic brake step of improved form and construction, and also a metallic brake step having hand brake gearing associated therewith. A still further object is to provide as a single, self-contained unit of construction a brake step and hand brake gearing, whereby the entire unit may be manufactured and assembled remote from the railroad or car building plant and later applied to the car as a single self-contained unit.

With these and other objects in view the invention consists of the formation, combination and arrangement of parts as will be herein described and claimed.

In the accompanying drawings, which show a preferred form of the invention, Figure 1 is a plan view of a brake step with hand brake gearing and other incidental parts attached thereto, the same being constructed in accordance with the principles of the present invention. Figure 2 is a partial front elevational view and partial vertical sectional view of the same, the sectional portion of the figure corresponding approximately to the irregular line 2-2 of Figure 5. Figure 3 is an end elevational view of the same and Figure 4 a vertical sectional view thereof taken approximately on the line 4-4 of Figure 5. Figure 5 is an inverted plan view of the same mechanism. Figure 6 is a vertical sectional view on the line 6-6 of Figure 1.

Referring to the drawings, the brake step is denoted by the numeral 6, the same being preferably of cast metal construction. The top surface of the same, upon which the operator stands, is preferably roughened or checkered as indicated at 7 and lightening or drain holes such as 8 may be supplied. These latter are indicated at the left hand end of Figure 1 only as it is optional whether or not they are supplied. The periphery of the step is preferably defined by a downwardly extending marginal flange or rib 9 which stiffens the edges of the step and prevents the starting of an edge crack. The slight extra depth presented by this depending flange has also an advantage of increased safety, not only from the fact that the brakeman's foot is not so likely to slip under it as under the otherwise thin metallic step, but injury by striking against the edge of the step is less likely. In addition the visibility of the step, particularly by lantern light, is increased. The brake step 6 is preferably affixed to the car body by means of suitable wrought iron supporting brackets 10, the rivets 11 being shown for securing the brackets 10 to the car body and the rivets 12 being supplied for securing the brake step to the brackets 10. In order that the brake step may be readily attached to the brackets 10, the step is provided with suitably arranged hollow bosses 13. The bottom surfaces of these bosses form stools which rest upon the top surfaces of the brackets 10, and the upper heads of the rivets 12 are let into the cavities of the bosses, which cavities comprise depressed pockets of suitable depth so that the said upper heads of the rivets 12 do not extend above the general plane of the top surface of the brake step.

A hand brake shaft or staff 14 of the usual type is employed, this carrying at its upper extremity the hand wheel 15 or other suitable means for operating the brake. A shaft bearing 16 of the usual type is also shown, the rivets for attaching the same to the car body being indicated at 17. The shaft 14 does not, as in many brake mechanisms, extend all the way to the chain drum, but only to the vicinity of the brake step. A second shaft 18 extends from the brake step to the bottom of the car where it may be provided with a chain drum 19 or other means for imparting movement and power to the brake chain 20 of the car. The chain is connected by the rivet 21 to an extended portion 22 of the drum, this latter comprising a quick take up whereby a large amount of slack may be taken up upon the first half-revolution of the drum 19. The drum 19 is preferably of square section for all of its length except the short

bottom trunnion portion 23 which has bearing in the staff bracket 24. A cotter 25 or other fastening may be employed to retain the trunnion 23 in position in the opening of 5 the bracket 24. The shaft aperture through the drum 19 is of course suitably shaped to fit over the square shaft 18 and rivet ears such as 26 may be provided for a rivet 27, to secure the drum to the shaft in a positive manner so 10 that under no conditions, even with the car turned over in a dumping machine, can the parts become accidentally disarranged.

Operatively interposed between the lower end of the shaft 14, which may for convenience be termed the low-powered shaft, and the upper end of the shaft 18, which latter may for distinction be termed the high-powered shaft, are suitable reduction gears, the preferable form being shown in the drawings. The lower end of the low-powered shaft 14 projects slightly through and below the brake step and is of square cross section, the upper portion of this shaft preferably being of circular cross section. Secured to 20 the squared lower end of the shaft 14 is a gear pinion 28, the same having an axially disposed opening arranged to receive the said shaft. The opening in the pinion 28 is shaped to conform to the shaft so that by simply 25 dropping the shaft into the opening of the pinion the two parts are rotatively secured together. The pinion is provided with an upper hub 29 which is of cylindrical form and arranged to have bearing within a pierced 30 boss 30 formed on the under face of the brake step. The opening for the accommodation of the hub 29 extends entirely through the brake step and the hub 29 preferably projects slightly above the top surface of the step. 35 Threaded upon the squared lower end of the shaft 14, and lying next above the gear pinion 28 is a ratchet wheel 31. The hub of the latter is shown as extended upward slightly to accommodate a rivet 32 which passes through 40 the same and through the shaft 14. A guard 33 is cast integral with the brake step and this is arranged to overlie the periphery of the ratchet wheel. The wheel being positively affixed to the shaft by means of the rivet 45 32 and the ratchet wheel in turn being prevented from rising by means of the guard 33, it will be seen that when the shaft is dropped through the squared opening of the ratchet wheel and into the squared opening 50 of the pinion 28 and the rivet 32 driven the parts are locked together for positive rotation and also in a manner to prevent accidental disarrangement even when the car is turned over in a dumping machine. A holding pawl 34 of the usual type is employed for 55 engaging the teeth of the ratchet wheel to hold the brake when the same is being used. This pawl is mounted on a vertical trunnion 35 which is cast integral with the brake step. 60 The trunnion is pierced to accommodate the

65 rivet 36 which holds the washer 37 over the top surface of the pawl 34. This washer is slightly larger than the bore of pawl so that after the latter has been dropped over the trunnion 35, the riveted washer will prevent 70 the removal of the pawl.

Attached to the under face of the brake step is the lower portion 38 of the gear casing or housing which embodies a bottom portion 39 with upright end portions or legs 40 75 which extend up to the brake step. The latter is provided with suitable hollow riveting bosses 41 which depend below the under surface of the brake step and comprise stools for the rivet flanges 42 of the member 38. Rivets 80 43 are employed for rigidly securing the member 38 to the brake step at the bosses 41, the upper heads of these rivets being let into cavities of said hollow bosses, the rivet heads accordingly being depressed with respect to 85 the top surface of the brake step. It will be noted that the rivet 36 which holds the pawl 34 in place is utilized as one of the rivets for securing the member 38 to the brake step. This is not only an economical construction 90 but ties the essential parts together in more certain relationship.

The high powered shaft 18 is located directly beneath and in axial alignment with the low powered shaft 14. This is especially 95 advantageous where new brakes are to be applied to existing cars wherein the locations of the hand brake wheel and of the chain drum must conform to existing conditions, usually represented by the single continuous 100 winding shaft or staff. The high powered shaft, as previously mentioned, is of square cross section. Mounted upon the upper end of the same is a gear wheel 43', the axial opening of the same being squared to fit the square 105 shaft 18. This gear wheel is provided with a lower cylindrical boss 44 which is rotatively positioned in a suitable opening in the bottom portion 39 of the member 38. A suitable boss 45 is formed on the member 38 and surrounds the said opening.

The pinion 28 is provided with a lower boss or trunnion 46 which fits within a co-operatively formed cylindrical cavity or bearing in the upper surface of the gear wheel 43', the trunnion and the cooperating bearing being axially arranged with respect to the shafts 14 and 18 as well as the gear members 28 and 43 mounted respectively thereupon. It will be seen that the gear pinion 28 is rotatively mounted at the top in the metal of the brake step while the gear wheel 43' is similarly mounted at the bottom in the member 38 rigidly secured to the brake step, and that these two gear members are socketed together midway between these bearing points. And while, as will be later explained, these two gears revolve at different speeds, yet the socketing of one within or upon the other will act to effectively support the ad- 110 115 120 125 130

jacent ends of both gear members. It will also be noted that the shaft 14 projects somewhat below the lower end of the bearing boss 30 and the shaft 18 projects above the upper limit of the bearing boss 45 in the member 38 for the gear wheel hub 44. This construction stabilizes the gear pinion 28 and gear wheel 43' so that the socketing of one within the other thereof, in addition to the ample proportions of the gear bearings themselves insures the gearing remaining at all times in proper alignment.

In order to transmit motion and power from the gear pinion 28 to the gear wheel 43' there is provided a set of integrally connected gear members embodying a gear wheel 46 which is arranged to mesh with the gear pinion 28 and a gear pinion 47 which in turn meshes with the gear wheel 43. As before stated, the gears 46 and 47 are cast integral with each other, the metal of the web 48 of the wheel 46 constituting also a shroud for the teeth of the pinion 47. Integral hubs 49 and 50 extend upward and downward respectively from the gears 46-47 and comprise journals for rotatively mounting this integral member within the gear housing formed by the brake step and the rigidly attached lower member 38, the hub 49 having bearing within the bearing boss 51 formed on the under face of the brake step and the hub 50 having bearing in a similar boss 52 formed on the member 38. The casting comprising the gears 46-47 and the hubs 49-50 may be cored out as indicated at 53 to facilitate manufacture. It is not necessary that the journal opening in the boss 51 extend all the way through the brake step and the drawings show the floor portion of the brake step as extending uninterruptedly over the same at 54. It should be mentioned that in Figure 5 the hidden portions of the several gear wheels and pinions are indicated merely by broken lines representing the pitch lines of the various gears.

Referring to Figure 1 it will be seen that the axis of rotation of the gears 46-47 is removed outwardly of the car body somewhat from that of the brake shafts and the gears mounted thereupon, the car body being indicated in this figure as well as in Figure 3 in dotted outline. This arrangement increases the stability of the parts, particularly of the member 38, the resistance of the same to overturning being increased. It also provides a space to the rear of the gear wheel 46 for the location of other parts of the car. This is desirable as occasionally it is desired by the car designer to arrange stakes, stiffeners or other members of the car body at about this location, and by disposing the two axes as shown and described the car designer is left free to arrange the other elements of the car to the best advantage.

63 The method of assembling the present

brake mechanism is as follows: The hub 29 of the pinion 28 is entered in the bore of the boss 30 and the hub 49 of the rotatable member comprising the gears 46 and 47 is entered in the bore of the boss or hub 51. The gear wheel 43' is then assembled in mesh with the pinion 47 and trunnioned on the lower end of the pinion 28. The member 38 is then assembled so that the bores of the hubs 45 and 52 fit over the hubs 44 and 50 respectively and the three rivets 43 are then driven. The pawl 34 is then placed over the integral trunnion 35, the washer 37 placed on top of the same, and the rivet 36 driven, thereby completing the securing of the member 38 to the 75 brake step with the gearing permanently contained in operative assembly in the housing formed by the step and the member 38. There is thus formed a complete assembly of brake step and gearing that may be put together 80 and tested out at a manufacturing plant remote from the car works and shipped there ready for attaching to the car. After being applied to the car as by means of the rivets 12 and brackets 10, the ratchet wheel 31 is 85 laid on the step and the shaft 14 with the hand wheel 15 already mounted dropped through the guide 16 and the said ratchet wheel and the rivet 32 driven, thereby completing the assembly of the low powered 90 shaft. It will of course be understood that if it is desired to use a guide 16 of a style that will not permit the passage of the squared lower end of the shaft 14, then the guide 16 must be riveted to the car after the shaft is in place. The lower or high powered shaft 18 may be slid up into the hub 44 of the gear wheel 43' from below, the chain drum 19 slid over the shaft and the rivet 27 driven. The bottom support bracket 24 is then put in 95 place and secured to some suitable part of the car. After coupling up the chain or other winding device, the mechanism is ready to 100 operate.

The operation will be readily understood from the description of the mechanism. It should be noted that when the hand wheel 15 is rotated in clockwise direction, which is usual when applying the brakes, the gear wheels 46-47 will be rotated at lower speed in counter-clockwise direction, and that the lower or high powered shaft 18 will be rotated in clockwise direction at still slower speed with consequently increased torque. This direction of rotation of the shaft 18 is important as most brake mechanisms are arranged in advance for the same and the usual car repairman is likely to be confused if the reverse direction of rotation is encountered. It should also be noted that the shaft 18 is arranged in axial alignment with the shaft 14. This is important, particularly where the mechanism is to be applied to existing cars to replace a hand brake the type employing a continuous shaft or staff.

There has thus been described a preferred form of the invention. Other forms are contemplated within the scope of the appended claims.

5. I claim:—

1. A metallic brake step having a housing member rigidly attached thereto, and hand brake reduction gearing mounted between the brake step and the housing member and directly journalled in each of the same with the end gears coaxially arranged, the ends of said housing being connected to said step at different distances from a longitudinal edge thereof for improving the stability of connection.
2. A hand brake mechanism for railway cars including a low powered shaft and a high powered shaft and reduction gearing operatively connecting the same, a metal brake step adapted to be secured to the body of the car, said reduction gearing being located below the brake step and involving gears with their axes of rotation arranged vertically and non-coincident, one of the said axes of rotation being located out of line with another thereof, both longitudinally and transversely of the car, a metal housing rigidly mounted beneath the brake step and with said step enclosing the gearing, and hubs on the step and housing providing bearings for the gearing.
3. A hand brake mechanism for railway cars including a high powered shaft and an aligned low powered shaft and reduction gearing operatively interposed between the same, a cast metal brake step and associated rigidly connected casting adapted to form a casing and provide bearings for the gearing, said gearing being rotatively mounted in and located immediately beneath the brake step, said reduction gearing involving gear members having non-coincident axes of rotation arranged upright to the brake step, one of the axes being located farther from the car body than another one thereof.
4. A hand brake mechanism for railway cars, including a cast metal brake step with a gear housing member rigidly secured thereto, reduction gearing arranged between the brake step and the housing member, said gearing involving a driving gear pinion and a driven gear wheel arranged beneath and in axial alignment with the driving pinion, and idler gears connected to a common spindle and arranged to mesh respectively with the driving pinion and driven wheel, the said spindle being journalled at one end in the brake step and at the other end in the said housing member, the adjacent ends of the said driving pinion and driven wheel being socketed one within the other, and the remote ends thereof being journalled, one thereof in the brake step and the other in the housing member, and high and low powered brake shafts connected respectively to the said driv-

ing gear pinion and the said driven gear wheel.

5. A hand brake mechanism, including a cast metal brake step adapted to be secured to the body of the railway car, the securing means involving a pair of brake step brackets carried by the car body, the same having flat projecting portions arranged to support the brake step, the brake step being provided on its lower surface with bosses arranged to contact with the said flat portions of the brake step brackets, and securing rivets passing through said bosses and through the flat portions of said brackets, the brake step being provided with depressions in its upper surface opposite said bosses, the upper heads of said securing rivets being arranged within said depressions.

6. A hand brake mechanism for railway cars including a cast metal brake step with reduction gearing arranged beneath the top surface of the same, a housing member removably affixed to the brake step, means for rigidly affixing the housing member to the brake step, hubs on said gearing, and bearing bosses formed in the said brake step and the said housing member, said gearing being held in operative position between the brake step and said housing member by said affixing means with the hubs directly received in said bosses and the end gears journalled one within the other.

7. As a unitary combination adapted for independent construction and connection with brake shafts, a combined cast metal brake step, gear housing and enclosed gearing comprising a cast metal brake step, a gear housing disposed therebeneath, means rigidly connecting said step and housing, a driving gear pinion and a driven gear wheel disposed between the step and housing and axially aligned, idler gears mounted on a common spindle and normally meshing respectively with the driving pinion and driven wheel, the upper end of said spindle being journalled in the brake step and the lower end in the housing member, the adjacent ends of said driving pinion and driven wheel being journalled one within the other, and the remote ends being journalled respectively in the brake step and housing member.

8. As a unitary combination adapted for manufacture and assembly remote from an associated car, a combined cast metal brake step, gear housing and enclosed gearing comprising a cast metal brake step, a gear housing disposed therebeneath, means rigidly connecting said step and housing, a driving gear pinion and a driven gear wheel disposed between the step and housing and axially aligned, idler gears mounted on a common spindle and normally meshing respectively with the driving pinion and driven wheel, said spindle being journalled in said brake step and housing member, said driving pin-

ion having an upwardly opening pocket adapted to receive a low powered brake shaft and the driven wheel having a downwardly opening pocket adapted to receive a high
5 powered brake shaft.

In testimony whereof I affix my signature.
